LET-OFF FOR LOOMS

Oscar V. Payne, Leicester, Mass., assignor to
Crompton & Knowles Loom Works, Worcester,
Mass., a corporation of Massachusetts

Application January 7, 1937, Serial No. 119,515

10 Claims. (Cl. 139—100)

This invention relates to improvements in let-offs for looms and it is the general object of the invention to provide a self-adjusting let-off responsive to variations in warp tensions.

5 The warp thread in certain types of looms rises from the beam and extends over a whip roll from whence it extends to the harnesses. It is a further object of my invention to provide means whereby movement of the whip roll regulates the turning of the warp beam, the force for turning the beam being derived from the warp.

10 It is a further object of my invention to provide a weighted let-off so constructed as to give a substantially uniform feed as the diameter of the warp beam diminishes.

15 It is a still further object of my invention to provide a let-off the regulating elements of which are in the form of an escapement which is controlled by the whip roll, the escapement being held against action when the whip roll is in its 20 rearmost position and being released to permit turning of the warp beam by forward motion of the whip roll.

25 It is a further object of the invention to cause the whip roll to have a parallel back and forth motion by means of a cross connection effective to apply the same pressure at each end of the whip roll.

30 With these and other objects in view which will appear as the description proceeds, my invention resides in the combination and arrangement of parts hereinafter described and set forth in the claims.

35 In the accompanying drawings, wherein a convenient embodiment of my invention is set forth,

Fig. 1 is a diagrammatic plan view of the rear part of a loom having my invention applied thereto,

40 Fig. 2 is an enlarged end elevation looking in the direction of arrow 2, Fig. 1, the weight being omitted.

Fig. 3 is a vertical section on line 3—3 of Fig. 2, and

45 Fig. 4 is a detail vertical section on line 4—4 of Fig. 2, on an enlarged scale.

Referring to the drawings, where there is shown the rear part only of the loom, the loom-sides 10 support rearwardly projecting brackets 11 provided with pockets 12 to receive the 50 gudgeons 13 of a warp beam 14. The warp W is led upwardly from the beam over a whip roll 16 and thence-forwardly to the harnesses not shown. The gudgeon 13 at one end of the beam may have keyed thereto a large gear 20 meshing 55 with a pinion 21 secured to a hub 22 of a gear

23 rotatable about a fixed stud 24 supported by a housing 18. The gear 23 meshes with a pinion 25 rotatable about a fixed stud 26 carried by the housing and rotating with a gear 27. The latter in turn meshes with a pinion 28 secured to a shaft 29 rotatable in a bearing 19 of the housing 18 bolted to the adjacent bracket 11.

10 The matter thus far described may be substantially the same as found in certain types of looms, the gears and pinions constituting a reduction gearing between the warp beam and the regulator therefor to be described. Except for the mounting of the whip roll the parts are substantially of the usual form.

15 In carrying my present invention into effect I provide each bracket 11 with a stand 30 and pivot to said stands right and left hand levers 31 and 32, respectively, movable about axes 33 supported by the stands. A rod 35 is pivoted at 20 36 to the lever 32 and is attached by means of an adjustable rod head 37 to pivot stud 38 carried by lever 31. The relative angular relation of the levers 31 and 32 can therefore be regulated and maintained, the levers moving in unison because of the rod 35.

25 Each of the levers 31 and 32 is provided with a pressure arm 40 which bears against a corresponding whip roll support 41 pivoted as at 42 to the bracket 11. Each support 41 has a foot 43 to engage a portion of the associated bracket 11 30 to limit rearward motion of the support, or motion to the left as viewed in Fig. 2. Each support is provided with a pocket 44 to receive a gudgeon 45 of the whip roll 16. By means of the supports 41 the whip roll is mounted for movement toward and from the front of the loom, the front of the loom as viewed in Fig. 3 being at the right. The arms 40 normally exert a rearward pressure on the supports tending to hold the whip roll in the rear or full line position 40 shown in Fig. 2.

35 The rod head 37 has pivoted thereto as at 50 a link 51 extending to the right as viewed in Fig. 1 and having pivotal connection as at 52 with a regulating lever 53 pivoted at 54 to an arm 55 45 secured to the adjacent bracket 11. There will ordinarily be but one regulator lever for both levers 31 and 32. A weight 56 is supported adjustably along the length of notched arm 57 of the lever 53 for the purpose of varying the 50 pressure exerted by the lever arms 40 on the whip roll supports 41.

30 The regulator lever 53 has an arm 60 connected at 61 to a rod head 62 of a depending rod 63, the lower end of which is pivoted as at 64 55

to a control lever 65. The rod head permits adjustment of the distance between axes 61 and 64. The control lever is pivoted as at 66 to the housing 18 and has an upwardly facing arcuate surface 68 for engagement with a pendulum 69 secured to the bottom of a rod 70 held in longitudinally adjusted position by a set screw 71 in a bearing 72. The bearing has integral therewith right and left escapement arms 73 and 74, respectively, having shoes 75 and 76, respectively. The bearing rocks on an eccentric stud 77 the shank 78 of which passes through the housing and is held in adjusted angular position by a nut 79.

15 The shoes are adapted for alternate cooperation with a toothed wheel 80 rigid with respect to pinion 28 and shaft 29, so that the pinion 28 and the wheel 80 rotate together with the stub shaft 29. The latter may have a bearing 81 in the cover plate 82 of the housing 18 and a hand wheel 83 on the shaft 29 permits the latter to be turned by the weaver. Bolts 84 may hold the cover in place on the housing and thereby fix the position of the bearing 81. The teeth 25 of the wheel 80 and the shoes are so related that the wheel can exert a lifting force on either of the shoes 75 or 76, one shoe only at a time having a working relation with the wheel 80.

In operation, the weight 56 will tend to turn 30 regulator lever 53 in a clockwise direction about its pivot 54 as viewed in Fig. 3 and cause the rod 35 and link 51 to be in their right hand position. The weight is therefore effective to position the arms 40 against the supports 41 and 35 hold the whip roll 16 to the rear, or in the full line position shown in Fig. 2, with the stop foot 43 against the bracket 11. With the whip roll rearmost the rod 63 is in its highest position and control lever 65 will be up with the arcuate 40 surface 68 pressing against the similarly formed pendulum 69. In this position of lever 65 the arcuate surface 68 is substantially concentric with stud 77.

45 The pendulum under these conditions will be to the right or full line position of Fig. 2 and shoe 76 will rest on tooth 91 of the wheel 80 in the path of advancing tooth 92. At the same time shoe 75 will be elevated to clear the teeth of wheel 80 but placed for movement toward tooth 50 93. Under these conditions the shoe 76 prevents rotation of wheel 80 because control lever 65 is in holding relation with the pendulum 96. The warp beam is therefore temporarily locked 55 against advance movement in a right hand direction as viewed in Fig. 2.

As weaving continues the whip roll will move 60 forwardly to the dotted position of Fig. 2 and the supports 41 will rock the levers 31 and 32 in a counter-clockwise direction about their axes 33, resulting in a left hand movement of rod 35 and link 51. There is a corresponding up movement of the weight 56 and down movement of rod 63, the latter moving the arcuate surface 68 of the lever 65 away from the pendulum and freeing the latter so that it can move in response to forces exerted by the wheel 80. Because of the tension on the warp the beam will thereupon 65 start to move in an advancing direction and tooth 70 92 will be forced against the shoe 76, moving the latter and therefore the pendulum to the dotted line position of Fig. 2. As shoe 76 leaves the wheel 80 the other shoe 75 will move in front of tooth 93. If the resultant advance motion of 75 the warp slackens the pressure on the whip roll

so that the latter moves back to its rearmost position lever 65 will move up against the pendulum and hold the latter in the dotted position of Fig. 2.

At the next operation of the motion the whip 5 roll will again move forwardly to depress lever 65 a second time, after which tooth 93, being now in the dotted position shown in Fig. 2, will lift the shoe 75 from the dotted tooth full line position shown in Fig. 2 and cause the pendulum 10 to move back to the full line position. The operation just described assumes that the rate of feed of the warp is such that a single motion of the pendulum will suffice to pay off enough yarn to return the whip roll to its rearmost position. 15

If the rate of feed is faster than that just described, however, the outward and return swing of the pendulum will occur consecutively and be accompanied by a single motion of the whip roll back to its rearmost position. The escape- 20 ment mechanism is such that any desired number of swinging motions of the pendulum can occur for each return motion of the whip roll to normal position.

Adjustment of the shoes 75 and 76 relatively 25 to the wheel 80 can be gotten by changing the angular setting of the stud 77 by a loosening and subsequent tightening of nut 79. This also effects a slight adjustment between the swing of the pendulum and the arcuate surface 68. 30

From the foregoing it will be seen that the weight tends normally to lock the pendulum and therefore prevent turning of the tooth wheel 80 and feeding of the warp, but forward movement of the whip roll causes the control lever to move 35 away from the pendulum, whereupon the wheel 80 is free to rotate to permit paying-off of the warp until backward movement of the whip roll induced by the weight again lifts the control lever 65 into locking relationship with the pen- 40 dum. The vertical adjustment of rod 70 permits proper location of the pendulum so that the latter can be locked by the lever 65 when the foot 43 is against its stop and the whip roll 45 is rearmost. It will further be seen that the releasing of the lock for the let-off is effected by forward movement of the whip roll, which in turn is caused by tightening the warp simultaneously with raising of the weight, and that the latter without substantial variation is effective 50 throughout the unwinding of the warp to maintain uniform feeding. The rod 35 together with its connections through levers 31 and 32 and the supports for the whip roll cause a parallel forward motion of the whip roll the effect of which 55 is to insure uniform tensioning of the warp throughout the length of the beam.

While I have described hereinbefore the action of the weight 69 and the lever 65 with reference to its extreme positions, yet I find in actual practice that the weight assumes a large variety of positions of rest along the arcuate surface 68 suggesting that the let-off action does not require a complete swing of the weight. The surface 68 acts as a brake to hold the weight in its various positions. Because of the relation between the wheel 80 and the escapement a comparatively light braking pressure between the lever 65 and weight 69 will suffice to hold the warp against advance feeding until the whip roll 70 has advanced sufficiently to cause a changed relation between the lever 65 and the weight. Because of the considerations just set forth the weight may in effect be considered as part of a braking device for the escapement and so far as 75

this feature of the invention is concerned the mass of the weight is of no particular consequence.

Having thus described my invention it will be seen that changes and modifications may be made therein by those skilled in the art without departing from the spirit and scope of the invention and I do not wish to be limited to the details herein disclosed, but what I claim is:

- 5 1. In a let-off for a loom, a rotatable warp beam tending to turn forwardly under tension of the warp, an escapement wheel connected to and turning with the beam, an escapement device oscillatable by a force derived from the escapement wheel and capable of preventing rotation of the wheel when oscillation of said device is prevented, brake means to prevent oscillation of the escapement device when the warp tension is normal, means actuated by increased tension 10 of the warp to move the braking means out of braking relation with respect to the escapement device, whereupon tension of the warp turns the beam and wheel, and means to return the braking means to braking relation with respect to the escapement device to prevent further rotation of the escapement wheel and beam when the warp tension returns to normal. 15
2. In a let-off for a loom, a warp beam tending to turn under action of the tension of the warp, an escapement wheel turning with the beam, an escapement device in engagement with the escapement wheel and tending to oscillate by a force derived from the wheel and capable when held against oscillation to prevent turning of the wheel and beam, preventing means operative when the warp tension is normal to hold the escapement device against oscillation, releasing means brought into action by an increased tension in the warp to move the preventing means 20 out of holding relation with respect to the device, whereupon the latter oscillates and the wheel and beam turn, and mechanism thereafter effective to restore the preventing means to holding relation with respect to the escapement device 25 when the warp tension returns to normal due to turning of the beam. 30
3. In a let-off for a loom, a warp beam tending to turn under action of the tension of the warp, an escapement wheel turning with the beam, an escapement device in engagement with the escapement wheel and tending to oscillate by a force derived from the wheel and capable of preventing turning of the wheel and beam when held against oscillation, a brake lever to prevent oscillation of the escapement device and cause the latter to prevent turning of the wheel, an element movable away from normal position when the warp tension is increased, connections 35 between the element and the lever to move the latter out of braking relation with respect to the escapement device when said element moves away from normal position due to increased warp tension, whereupon the wheel causes the escapement device to oscillate and turn to permit turning of the beam under action of the warp, and means effective after the warp tension is reduced by turning the beam to return said element to normal position and return the brake lever to holding relation with respect to the escapement device. 40
4. In a let-off for a loom, a warp beam tending to turn under action of the tension of the warp, an escapement wheel turning with the beam, an escapement device in engagement with the escapement wheel and tending to oscillate by a 45
5. In a let-off for a loom, a warp beam tending to turn under action of the tension of the warp, an escapement wheel turning with the beam, an escapement device in engagement with the escapement wheel and tending to oscillate by a force derived from the wheel and capable of preventing turning of the wheel and beam when oscillation thereof is prevented, a whip roll movable forwardly from normal position by increased warp tension, a weight to move the whip roll rearwardly, brake means for the escapement device normally preventing oscillation of the latter and causing the same to prevent turning of the escapement wheel, connections between the whip roll and the brake means to move the latter out of braking relation with respect to the escapement device when the whip roll moves forwardly, the weight falling when the warp tension is reduced by turning the beam to return the whip roll to normal rearward position and restore the brake means to holding relation with respect to the escapement device and prevent further oscillation of the latter. 50
6. In a let-off for a loom, a rotatable warp beam, an escapement wheel, means to gear the wheel to the beam to cause the wheel and beam to turn together, an escapement device to engage the wheel and capable when locked of preventing movement of the latter, holding means normally effective to lock the escapement device in position to prevent movement of the wheel, a whip roll movable forwardly in response to pressure of the warp of the beam, and connections between the whip roll and the holding means to disconnect the latter from the escapement device when the whip roll moves forwardly, the whip roll and beam being thereby rendered free to rotate under action of the warp thread. 55
7. In a let-off for a loom, a rotatable warp beam, an escapement wheel, means to cause the latter to rotate with the beam, a pivoted escapement device for the wheel capable when locked of preventing rotation of the latter, a control lever for the escapement device having an arcuate surface, means moving with the escapement device to engage the arcuate surface to lock the escapement device in position to prevent rotation of the escapement wheel, a whip roll movable in response to pressure of the warp thread of the beam, and connections between the whip roll and the control lever to move the latter to a position to release the escapement device, whereupon pressure of the warp threads turn the warp beam and escapement wheel. 60
8. In a let-off for a loom, a rotatable warp beam, an escapement wheel connected to and 65
- 70
- 75

- turning with the beam, an escapement device for the escapement wheel, preventing means normally holding the escapement device in position to restrain rotation of the escapement wheel,
- 5 5. a whip roll movable forwardly by pressure of the warp thread of the beam, weight means to move the whip roll rearwardly, and connections between the whip roll, weight means and the preventing means of the escapement device effective when
- 10 the whip roll is moved forwardly by pressure of the warp to disconnect the preventing means from the escapement devices and lift the weight means, thereby releasing the escapement wheel to render the warp thread effective to turn the beam and
- 15 15. wheel, the weight means to be effective to move the whip roll rearwardly and restore the preventing means to normal holding relation with respect to the escapement device after movement of the escapement wheel.
- 20 9. In a let-off for a loom, a rotatable warp beam, an escapement wheel connected to and rotating with the beam, an escapement device for the escapement wheel capable of preventing rotation of the latter when said device is held against
- 25 movement and the wheel being free to turn when the device is free, holding means for the escapement device to hold the latter in a position to prevent turning of the escapement wheel, a whip roll movable forwardly in response to pressure of
- 30 the warp thread of the beam, two levers, one for each end of the whip roll, to exert backward pressure on the whip roll, said levers movable forwardly with the whip roll, connections between said levers and the holding means to move the
- 35 latter out of holding relation with respect to the

escapement device to free the latter when the whip roll moves forwardly, the wheel being thereupon free to turn, and force exerting means attached to said connections to move the levers in a direction to move the whip roll rearwardly and effective to move the holding means into holding relation relatively to the escapement device and render the latter effective to prevent turning of the wheel and beam.

10 10. In a let-off for loom, a rotatable warp beam, an escapement wheel connected to and rotating with the beam and having teeth, an oscillatable escapement device having two spaced shoes which alternately have holding relation with respect to the wheel, either shoe when engaging a tooth of the wheel preventing rotation of the latter when oscillation of the device is prevented, the wheel tending to turn under the force of the warp thread when one shoe moves away from the wheel and the other shoe moves toward said wheel, holding means for the escapement device to prevent oscillation of the device and retain the latter with either shoe in contact with the wheel, a whip roll movable forwardly under pressure of the warp of the beam, and connections between the whip roll and the holding means to transmit a force from the whip roll to said holding means and move the latter out of holding relation with respect to the escapement device when the whip roll moves forwardly to release said escapement device, whereupon the wheel turns to oscillate the escapement devices to permit turning of the warp beam and move one shoe away from and the other shoe toward said wheel.

OSCAR V. PAYNE. 35
